(57) **CLAIM**

The ornamental design for a bumper of a medical pump, as shown and described.

DESCRIPTION

FIG. 1 is a front, top, and right side perspective view of the bumper of a medical pump, showing my new design;

FIG. 2 is a rear, top and right side perspective view thereof;

FIG. 3 is a top plan view thereof;

FIG. 4 is a bottom plan view thereof;

FIG. 5 is a front side elevational view thereof;

FIG. 6 is a rear side elevational view thereof;

FIG. 7 is a right side elevational view thereof;

FIG. 8 is a left side elevational view thereof;

FIG. 9 is a front, top, and right side perspective view of a second embodiment of the bumper of a medical pump, with the door of the medical pump in a closed position;

FIG. 10 is a rear, top and right side perspective view thereof, with the door of the medical pump in a closed position;

FIG. 11 is a top plan view thereof, with the door of the medical pump in a closed position;

FIG. 12 is a bottom plan view thereof, with the door of the medical pump in a closed position;

FIG. 13 is a front side elevational view thereof, with the door of the medical pump in a closed position;

FIG. 14 is a rear side elevational view thereof, with the door of the medical pump in a closed position;

FIG. 15 is a right side elevational view thereof, with the door of the medical pump in a closed position;

FIG. 16 is a left side elevational view thereof, with the door of the medical pump in a closed position; and,

FIG. 17 is a front, top, and right side perspective view of the second embodiment of the bumper of a medical pump with the door of the medical pump in an open position and an infusion tube loaded into the door.

The broken lines shown in the figures represent portions of article that form no part of the claimed design.
